UNITED STATES PATENT OFFICE.

KENNETH C. LINE, OF CHICAGO, ILLINOIS, ASSIGNOR TO GEORGE B. GRINDE, OF CHICAGO, ILLINOIS.

SURGICAL SPLINT.

Application filed July 25, 1925. Serial No. 46,024.

This invention relates to a surgical splint, particularly to a splint to be used with broken legs to support and hold the leg stiff and to permit the wearer to walk upon the splint before the bones have completely knit. The invention is illustrated more or less diagrammatically in the accompanying drawings, wherein:

Figure 1 is a side elevation of the splint in place;

Figure 2 is a front elevation with parts omitted;

Figure 3 is an enlarged side elevation of the upper end of the splint;

Figure 4 is a rear view of the same;

Figure 5 is an inside view showing the attachment of the upper collar to one of the side members;

Figure 6 is a section taken at the line 6—6 of Figure 3 on an enlarged scale showing a portion of the upper end of the splint;

Figure 7 is a bottom elevation showing the operating mechanism;

Figure 8 is a vertical cross section taken on the line 8—8 of Figure 7;

Figure 9 is a section taken on line 9—9 of Figure 1;

Figure 10 is a detailed cross section showing one of the adjustable leg retaining members; the section being made at line 10—10 of Figure 9;

Figure 11 is an elevation with parts in section showing one of the leg supporting members;

Figure 12 is an elevation of a combined operating key and screw driver.

Like parts are designated by like characters throughout.

A, A are hollow side members. They are preferably rectangular in cross section.

B is a hollow base portion having two upwardly extending perforated lugs B¹ B¹. Upon each of these lugs B¹ is seated one of the side members A.

C, C are upper side members adapted to be telescoped within the lower members A. Each of the upper members C is provided in its lower end with a threaded plug C¹.

D, D are threaded rods which are threaded into the threaded plugs C¹. Each of them

is provided adjacent its lower end with a smooth portion D¹ which lies within the perforation in the lug B¹. At its lower end each of the members D carries a pinion D² which lies within the hollow portion of the base member B. The base member B is normally closed by a cover plate B² which in the preferred form has on its outer or working face an elastic or shock absorbing cover B³. Mounted within the member B is a main driving pinion D³ which is preferably provided with an angular perforation D⁴. Mounted also within the base portion B are two gears D⁵ D⁶. Each of them is mounted on a movable bolt D⁶ D⁶ which bolt is normally held up in position shown in the left of Figure 8, by means of the spring D⁷. When the gear is in this position it meshes with the driving pinion D³ and the pinion D² on the member D. For the purpose of throwing one or the other of the screws out of operation, the bolt D⁹ may be depressed against the action of the spring D⁷ and the gear which it carries is thrown out of mesh with the pinion D². Thus one of the screws is thrown out of operation and the other may be rotated alone. Rotation of the screws serves to move in or out the upper telescoping members C, and by means of this rotation the side members of the splint may be lengthened or shortened at the will of the operator and may be moved together or separately.

F is an operating tool having the squared end F¹ adapted to be inserted into the opening D⁴ whereby the driving pinion D³ may be rotated. F² is a screw driver on the tool adapted for use as a screw driver in connection with other adjustments to the splint.

G is a rest or support pivoted adjacent the bottom of the splint. When the splint is in the erect or upright position it swings down into the position shown in full lines in Figure 1. When the wearer is lying down the rest G swings into the position shown in dotted lines in Figure 1, and thus automatically supports the splint and with it the limb of the wearer.

Adjustably mounted at suitable intervals along the member C are clips H. These clips as shown are formed of two members

and have tightening bolts H^1 . The bolts may be loosened and the members slipped over the splint to a suitable location. The bolts are then tightened and the parts held in adjustment.

Pivots mounted on each of these members is a strap engaging clamp I . Each of these clamps is formed of two members as shown and between the members a strap portion I^1 passes. The two members of the clamp I are fastened together by adjusting nuts I^2 , and these nuts may be loosened to permit the strap to be slipped for adjustment through the clamps and then to tighten it in the adjusted position. The strap member is provided with a flap I^3 which may be of any fabric and is preferably supplied with stiffening members I^4 . I^5 I^5 are attaching straps adapted to fasten together the adjacent ends of the strap members I^1 . These members I^5 are preferably provided with perforations substantially throughout their entire length and they are fastened at each end to buckles I^6 on the member I^1 . I^7 I^7 are curved supporting members adapted to hold the limb of the wearer in place, and they are themselves supported in the straps I^1 . They may be of any suitable form. In the preferred form herewith illustrated they are made of a metal center I^8 and the exterior is cloth.

J is a boot or stirrup in which the foot of the wearer is positioned. It is supported from the side members by means of an adjustable strap J^1 . When the wearer is upright and walking the foot is carried in this member J , which is omitted in Figure 2 for the purpose of clearness. J^2 J^2 are straps which may be adhesive material fastened to the limb of the wearer or the dressing of the limb. J^3 J^3 are straps, each of which is fastened at one end to a side member A by means of a buckle J^4 . At its other end each of the members J^3 carries a buckle J^5 and to this buckle the lower end of the strap J^2 is secured. The straps J^3 pass under the cleats J^6 on the member B . When the side members are extended, tension is exerted on the strap J^3 and through it on the strap J^2 and the limb of the wearer is extended.

Fastened to each of the upper side members C on its inside is an attaching plate K . It is held preferably by means of screws K^1 . Mounted between the plate K and the side members C and supported largely by the upper screw K^2 is a locking plate L . This plate is mounted on the upper screw K^2 for slight pivotal movement to permit some rocking adjustment. Each of the plates L adjacent its front end has removably and adjustably mounted upon it a strap and buckle L^1 L^1 . Adjacent its rear it has mounted upon it a buckle L^2 . L^3 is a loop shaped supporting and retaining member which is bent around so as to rest at one end upon one

of the members L and at the other end upon the other member L . It has adjacent its upper edge a number of supporting cleats or hooks L^4 , and adjacent its lower edge a number of steady or engaging hooks L^5 . Its upper edge is slotted and bent outward as at L^6 , and thus the upper edge is somewhat springy. Fastened to this slotted and outwardly bent upper edge is a padding M which may be of any suitable nature. It may be of felt or spongy rubber or any other cushioning material. Adjacent each end of this padding is fastened on its outer edge a loop M^1 which is adapted to receive the strap and buckle O^1 . Surrounding the entire upper end of the splint and overlying the padding just mentioned as well as the plates above described is an additional cushioning shield N , which may be of spongy rubber or other cushioning material. It is preferably covered with a removable and washable cover N^1 which overlies the member L^3 and extends substantially about the entire splint. Adjacent its ends it is perforated so that the buckles and straps L^1 , M^1 may pass through to engage additional straps O , O^1 . By means of these straps the two edges of the plate L^3 may be drawn together. Further adjustment is provided by means of a strap O^2 which engages the two buckles L^2 L^2 which are fastened to the plates L in the rear of the splint.

The plate members L and L^3 are preferably made of somewhat flexible metal, and thus they can be bent and sprung to permit adjustment by the tightening or loosening of the various straps which hold them. The entire ring assembly about the upper end of the splint is supported from the plates L , and these as was mentioned above, are mounted for some pivotal or tilting movement and thus the entire ring assembly may be rocked backward and forward to permit of adjustment. This rocking is preferably carried out by loosening the upper screw K^2 and when the ring has been tilted to the proper angle the screw is tightened and the set screw P is tightened against it.

Each of the upper members C^1 is provided with a perforation Q . R is a side member provided with perforated inwardly bent ears R^1 adapted to overlie the upper end of one of the members C . By means of a bolt R^2 , the member R is pivotally supported from the perforation Q at the upper end of the side member C . The perforation is mounted close to the upper end and thus considerable lateral flexure of the part R is possible without interference with the other members of the splint. By this means some lateral movement of the limb of the wearer is possible.

S is an upper member provided with a plurality of perforations S^1 adapted by

means of a bolt S^2 to be adjustably supported on the member R . S^3 is a retaining ring adapted to hold the two members against relative pivotal movement.

- 5 T is a belt supported from the member R , provided with straps T^1 T^2 by means of which it may be adjusted and tightened. U is a belt supported adjacent the upper end of the member S , provided with straps U^1 by means of which it may be adjusted and tightened. Each of the belts T and U is supported from the side member which carries it, and thus slight rotary or pivotal movement of each of the belts with relation 10 to the member to which it is attached is possible.

Although I have shown an operative device, still it will be evident that many changes might be made in size, shape and 15 arrangement of parts without departing materially from the spirit of my invention, and I wish therefore that my showing be taken as in a sense diagrammatic.

The use and operation of my invention 20 are as follows:

When a leg has been broken and it is desired to use a splint of the type shown herewith, the bones are first set and then the splint is adjusted to the wearer, being generally adjusted to the shape and size of the limb before being put in place. The side members by means of the key and gears at the bottom of the splint are elongated or shortened, the straps for the lower part of 30 the limb are adjusted up or down, tightened or loosened, and tilted to conform to the form of the limb of the individual, and the upper ring member is also adjusted. The splint is then set in place about the limb and the straps tightened to hold the limb rigid within the splint. Some form of taping or other arrangement is used whereby the foot is held down in the splint and thus traction can be applied by elongating the splint side 40 members, and tension put on the limb to hold it or to extend it.

The upper extension member is fastened about the body of the wearer and holds the limb properly supported. As conditions 45 change an adjustment of all the parts of the splint can be carried out. One or the other of the side members may be lengthened or shortened or may be moved together. The straps which hold the cloth and the upper 50 part of the limb together with the splint members which they carry can be pivoted about their support and they can be raised or lowered along the side members of the splint, and they can be tightened or loosened. 55 The upper ring member may be similarly treated and may be rocked backward and forward to one side or the other and it may be raised or it may be tightened at the will of the operator.

60 65 I claim:

1. In combination in a surgical hip, leg and foot splint an extensible longitudinal member, means for moving this member in or out, said longitudinal member joined at its bottom to a base portion and carrying adjacent its upper end a supporting collar, said collar being slidably and pivotally mounted upon said member. 70

2. In combination in a surgical hip, leg and foot splint a plurality of extensible longitudinal members, selective mechanical means for moving said members in or out in unison and separately, said members joined at their bottom to a base portion, and being additionally joined adjacent their upper ends by a supporting collar, said collar being slidably and pivotally mounted upon said longitudinal members. 75

3. In combination in a surgical hip, leg and foot splint a plurality of extensible longitudinal members, selective mechanical means for moving said members in or out in unison and separately, said members joined at their bottom to a base portion, the moving mechanism being included therein, and being additionally joined adjacent their upper ends by a supporting collar, said collar being slidably and pivotally mounted upon said longitudinal members. 80

4. In combination in a surgical hip, leg and foot splint an extensible longitudinal member, mechanical means for moving this member in or out, said longitudinal member joined at the bottom to a base portion and carrying adjacent its upper end a supporting collar, said collar being slidably and pivotally mounted upon said member, and being provided with means whereby it may be reduced or enlarged in diameter. 95

5. In combination in a surgical hip, leg and foot splint an extensible longitudinal member, mechanical means for moving this member in or out, said longitudinal member joined at the bottom to a base portion and carrying adjacent its upper end a supporting collar, said collar being slidably and pivotally mounted upon said member, and being provided with means whereby it may be reduced or enlarged in diameter, said collar formed at its upper edge of spring material. 105

6. In combination in a surgical hip, leg and foot splint a plurality of extensible longitudinal members selective mechanical means for moving said members in or out in unison and separately, said members joined at their bottom to a base portion, and being additionally joined adjacent their upper ends by a supporting collar, said collar being slidably and pivotally mounted upon said longitudinal members, and being provided with means whereby it may be reduced or enlarged in diameter, said collar formed at its upper edge of spring material. 110

7. In combination in a surgical hip, leg 120

- and foot splint a plurality of extensible longitudinal members, selective means for moving said members in or out in unison and separately, said members joined at their bottom to a base portion, the moving mechanism being included therein, and being additionally joined adjacent their upper ends by a supporting collar, said collar being slidably and pivotally mounted upon said longitudinal members, and being provided with means whereby it may be reduced or enlarged in diameter, said collar formed at its upper edge of spring material and carrying additionally thereupon a cushioning part.
15. In combination in a surgical hip, leg and foot splint a plurality of extensible longitudinal members, selective means for moving said members in or out in unison and separately, said members joined at their bottom to a base portion, the moving mechanism being included therein, and being additionally joined adjacent their upper ends by a supporting collar, said collar being slidably and pivotally mounted upon said longitudinally members, and being provided with means whereby it may be reduced or enlarged in diameter, said collar formed at its upper edge of spring material and carrying additionally thereupon a removable cushioning part.
9. In combination in a surgical hip, leg and foot splint an extensible longitudinal member, means for moving this member in or out, said longitudinal member joined at its bottom to a base portion and carrying adjacent its upper end a supporting collar, said collar being slidably and pivotally mounted upon said member, there being supported on said longitudinal member intermediate its ends a limb supporting and engaging part slidably and pivotally mounted.
10. In combination in a surgical hip, leg and foot splint a plurality of extensible longitudinal members, selective means for moving said members in or out in unison and separately, said members joined at their bottom to a base portion, the moving mechanism being included therein, and being additionally joined adjacent their upper ends by a supporting collar, said collar being slidably and pivotally mounted upon said longitudinal members, and being provided with means whereby it may be reduced or enlarged in diameter, said collar formed at its upper edge of spring material and carrying additionally thereupon a removable cushioning part, there being supported on said longitudinal members intermediate their ends, a limb supporting and engaging part slidably and pivotally mounted.
11. In combination in a surgical hip, leg and foot splint an extensible longitudinal member, means for lengthening or shortening said members, said longitudinal member joined at its bottom to a base portion and carrying adjacent its upper end a supporting collar, said collar being slidably and pivotally mounted upon said member, and means for locking said collar in any suitable adjusted position.
12. In combination in a surgical hip, leg and foot splint a plurality of extensible longitudinal members, selective means for lengthening or shortening said members in unison and separately, said members joined at their bottom to a base portion, and being additionally joined adjacent their upper ends by a supporting collar, said collar being slidably and pivotally mounted upon said longitudinal members, and means for locking said collar in any suitable adjusted position.
13. In combination with a surgical hip, leg and foot splint a supporting and engaging collar slidably mounted upon said splint and adapted to be rotated with relation thereto, and means for locking the same in adjusted position against further rotation, said collar adapted to be moved with relation to said splint wholly or in part.
14. In combination with a surgical hip, leg and foot splint a supporting and engaging collar slidably mounted upon said splint and adapted to be rotated with relation thereto, and means for locking the same in adjusted position against further rotation, said collar adapted to be moved with relation to said splint wholly or in part, and means for enlarging or reducing the diameter of the collar.
15. In combination with a surgical hip, leg and foot splint a supporting and engaging collar slidably mounted upon said splint and adapted to be rotated with relation thereto, and means for locking the same in adjusted position against further rotation, said collar adapted to be moved with relation to said splint wholly or in part, and means for enlarging or reducing the diameter of the collar, said collar being formed of a band bent in partially circular form and provided with tensioning devices adapted to draw its ends closer together or to permit them to separate.
16. In a surgical hip, leg and foot splint provided with longitudinal members adapted for expansion and contraction, and operating means therefor, including a train of gears, and a main gear adapted to be rotated to cause movement of the longitudinal member, and a plurality of controlling gears one for each of said longitudinal members, each of such controlling gears separately adjustable whereby it may be thrown out of operation and the mechanism may thereafter be operated without operating the longitudinal member controlled by said controlling gear.
17. In combination in a surgical hip, leg

and foot splint an extensible longitudinal member, means for shortening and lengthening such member, the collar on said member adapted to be positioned about a leg and 5 a hip immobilizing attachment adapted to be fastened to such extensible member and to pass along the body of the wearer, in com-

bination with a belt movably attached to such hip immobilizing device and embracing the body of the wearer.

10

Signed at Chicago, county of Cook and State of Illinois, this 23rd day of July, 1925.

KENNETH C. LINE.
